John Straub,

BY

Geo. P. Kimmel. ATTORNEY.

UNITED STATES PATENT OFFICE.

JOHN STRAUB, OF ASHLEY, NORTH DAKOTA.

BOTTLE STOPPER.

Application filed April 29, 1927. Serial No. 187,545.

The invention relates to a closure, and more especially to the class of bottle stoppers and extractors therefor.

The primary object of the invention is the provision of a closure of this character, wherein the same is exemplified as a stopper to be conveniently inserted in the mouth of a container, such as a bottle, whether it be a soft drink containing bottle, milk bottle, medicine bottle, or the like, to positively seal the mouth of the container and will be readily removable therefrom, without the use of a corkscrew or other opener or extractor, which ordinarily mutilate or damage the closure, especially where it is required to constantly remove the closure from the mouth of the container.

Another object of the invention is the provision of a closure of this character, wherein the same is of a novel construction so that the mouth portion of the container will be firmly gripped both interiorly and exteriorly thereof, so as to positively and firmly seal the container and when it is desired to open the container, the medium for the extraction of the closure will initially operate to release the gripping action of the closure exteriorly of the mouth portion of the container and finally on an outward pull the closure will be extracted from engagement in the mouth of the container.

A still further object of the invention is the provision of a closure of this character, wherein the same simulates a stopper adapted to be engaged in the mouth of a container, exemplified as a bottle, and when so engaged the exterior surface of the mouth portion of the bottle will be firmly gripped and sealed, to assure the retention of the closure in the mouth of the bottle for the closing thereof, without liability of the accidental slipping out of the closure from the mouth of the bottle.

A still further object of the invention is the provision of a closure of this character, wherein the construction thereof is novel in form, as the said closure is equipped with a means operable to initially release the gripping action of the closure exteriorly of the mouth portion of the container and to finally extract the closure from the mouth of the container, without excessive labor on the part of the operator and at the same time without liability of damage or mutilation of the closure, thereby assuring increased usage of such closure.

A still further object of the invention is the provision of a closure of this character, which is extremely simple in construction, thoroughly reliable and efficient in its purpose, strong, durable and inexpensive to manufacture.

With these and other objects in view, the invention consists in the features of construction, combination and arrangement of parts, as will be hereinafter more fully described in detail, illustrated in the accompanying drawing and pointed out in the claims hereunto appended.

In the accompanying drawing:

Figure 1 is a fragmentary elevation of a container, exemplified as a bottle, showing the closure constructed in accordance with the invention, sealing the mouth of the bottle.

Figure 2 is a vertical sectional view through the bottle neck and stopper, showing the latter in sealing position and engaged in the mouth of said bottle.

Figure 3 is a view similar to Figure 2 showing the initial position of the closure when pulled upon for removal of the closure from the mouth of the bottle.

Figure 4 is a fragmentary elevation of a portion of the mouth of the bottle and the closure, the latter having been released or extracted from the mouth of the bottle.

Figure 5 is a top plan view of the closure for the bottle.

Figure 6 is a fragmentary detailed vertical sectional view showing a slight modification of the device.

Similar reference characters indicate corresponding parts throughout the several views in the drawing.

Referring to the drawing in detail A designates a portion of a container, exemplified as a bottle having the usual externally beaded open mouth B, it being understood of course that the container A constitutes no part of the present invention and is merely illustrated in the form shown to disclose the application of the closure forming the present invention, hereinafter fully described.

The closure comprises what might be termed a stopper, including a body 6, preferably made from rubber, although the same may be made from any other suitable material having the required resiliency or elasticity and is formed with a head 7 provided with a reduced central tapered portion 8 which is adapted to be inserted into the

mouth B of the container A, in a like manner as an ordinary cork stopper would be engaged in the mouth of said bottle or container. The portion 8 is of considerably less size than the head 7, which in this instance is of substantially circular formation and from the marginal edge of said head extends concentrically with respect to the tapered portion 8 an annular rim 9, having the required inherent resiliency or elasticity to snugly embrace the mouth portion B of the container A externally thereof as is clearly shown in Figures 1 and 2 of the drawing.

15. The disposition of the tapered portion 8 and the rim 9 relative to each other provides therebetween a deep channel for accommodating the mouth portion B of the container A and at the inner end of this channel in 20 the wall of the rim 9 at the inner face thereof is formed a groove 10 which in its contour corresponds to the bead externally on the mouth edge of the container A, so that when the portion 8 is forced into the mouth the 25 rim 9 will encircle the outer wall of the portion B of the container and the external bead at the mouth of the container A will become seated in the groove 10, so that the stopper will seal the mouth B of the container A as will be clearly apparent in 30 Figure 2 of the drawing.

Formed centrally of the head 7 is a pull strap 11, which may be integral with the head or permanently connected thereto in 35 any desirable manner and is preferably made from rubber, although the same may be made from any other suitable material having inherent resiliency or elasticity. This pull strap 11 at its outer end merges into a plurality of pull straps 12, these being disposed in opposite relation to each other and extend downwardly beyond opposite sides of the stopper body 6 and have their end portions remote from the juncture of the strap 40 11 therewith merging into the rim 9 or integrally formed therewith, yet these end portions may be otherwise permanently fastened to the rim 9 if found desirable.

The purpose of the pull straps 12 is to 50 exert a pulling action on the rim 9 of the stopper body 6 to initially cause this rim to curl outwardly and upwardly as is shown in Figure 3 of the drawing, thereby breaking contact between the rim and the outer surface of the mouth B of the bottle or 55 container A, whereupon the strap 11 is finally pulled upon so as to readily and conveniently extract the portion 8 of the body 6 of the stopper from the mouth of the container A for the opening thereof.

The connected arrangement of the straps 11 and 12 with each other presents loop formations, for the fingers of the operator of the closure, so that proper pulling action 60 65 can be had on the said straps for the initial

release of the closure and the final extraction thereof from the mouth B of the container A, this being clearly obvious from Figures 2, 3 and 4 of the drawing.

In the application of the closure it is only 70 necessary to center the portion 8 relative to the open mouth B of the container A and thereafter press the closure so that the same will be forced inwardly relative to the mouth of the container, causing the portion 8 to 75 telescope in the open mouth B and the rim to ride over the bead at the edge of the mouth B, until the bead becomes seated in the groove 10 between the portion 8 and the rim 9 and thereafter the rim will snugly 80 fit about the mouth B of the container A and frictionally contact with the external surface of said mouth B as is clearly shown in Figures 1 and 2 of the drawings. In this manner the container A will be closed at its 85 mouth B and firmly sealed.

With reference to Figure 6 of the drawing, there is shown a slight modification of the invention, wherein the container A has formed at its mouth edge a relatively pronounced external bead B, while the closure for the head 7' is formed with a center disc-like table 8' at the mouth B of the container A as is clearly shown and is surrounded concentrically with an annular rim 9' having 90 the required inherent resiliency or elasticity to snugly embrace the mouth B of the container A externally thereof. The head and rim 7' and 9' respectively are provided with the pull straps 11' and 12', these simulating 100 the pull straps hereinbefore described. The rim at its inner face is formed with the usual channel or groove 10' to accommodate the bead on the mouth B of the container.

From the foregoing it is thought that the construction and manner of application of the closure to the container A will be clearly understood and also the mode of release of the closure, so a more extended explanation 105 has been omitted.

What is claimed is:—

1. A closure of the character described, comprising a body formed with a central stopper-like extension engageable in the mouth of a container, a yieldable rim formed on the body, spaced from and concentrically disposed relative to the extension to frictionally engage the external surface of the mouth portion of the container, and pull means located externally on the body and connected with the latter and said rim for initially lifting the rim to break contact thereof with the mouth portion of said container and to subsequently extract the cork extension of the body from the mouth of said container, said means including a plurality of elastic straps connected with each other and to the body and rim, respectively.

2. A closure of the character described comprising a body formed with a head

having a central stopper-like extension to engage in the mouth of a container, a resilient rim formed marginally of the head and disposed concentrically of the extension 5 to frictionally engage the external surface of the mouth portion of said container, a plurality of pull straps connected with the rim to initially break the contact of the latter with the mouth portion of said container, an

extractor strap connected with the head and with the first named straps and adapted to effect the removal of the extension from the mouth of the container when said strap is pulled upon subsequently to the pulling action upon the first named straps. 10 15

In testimony whereof, I affix my signature hereto.

JOHN STRAUB.
